(57) **CLAIM**

The ornamental design for a cushioned storage device for vehicle seats, as shown and described.

DESCRIPTION

FIG. 1 is a perspective view of a cushioned storage device for vehicle seats showing my new design;

FIG. 2 is a top view of thereof;

FIG. 3 is a bottom view thereof;

FIG. 4 is a right side elevational view thereof;

FIG. 5 is a left side elevational view thereof;

FIG. 6 is a rear elevational view thereof;

FIG. 7 is a front elevational view thereof; and,

FIG. 8 is an environmental view of the cushioned storage device for vehicle seats of FIG. 1 positioned on a vehicle seat; the broken lines forming no part of the present invention.
